UNITED STATES PATENT OFFICE

JOHN RUFFING, SR., OF NOKOMIS, ILLINOIS, ASSIGNOR OF ONE-HALF TO WARREN C. ARGUST, OF TAYLORVILLE, ILLINOIS

MINER'S CAP

Application filed January 14, 1931. Serial No. 508,778.

This invention appertains to new and useful improvements in miners' caps and more particularly to a cap which has as its principal object the provision of means for protecting the scull of the wearer.

Another important object of the invention is to provide a miner's cap provided with means whereby the cap may be adjusted to the head of the wearer.

Another important object of the invention is to provide a cap provided with socket means for accommodating lamps of various types.

These and other important objects and advantages of the invention will become apparent to the reader of the following specification and claim.

In the drawings:—

Figure 1 represents a side elevational view 20 of the cap.

Fig. 2 represents a top plan view of the cap.

Fig. 3 represents a front elevational view of the cap.

Fig. 4 represents a cross sectional view of 25 the protective crown.

Fig. 5 represents a perspective view of the lamp retaining spring.

Fig. 6 represents a fragmentary detailed 30 sectional view of the cap.

Fig. 7 represents a fragmentary perspective view looking at the inside of the lamp supporting frame.

Fig. 8 represents a perspective view of the 35 socket unit.

Referring to the drawings wherein like numerals designate like parts, it can be seen that numeral 5 represents the metallic crown which is provided with reinforcing ribs 6, and a depending flange 7 to which the split apron

40 8 is secured and from which the same depends. The ends of the apron 8 are secured together by suitable lacings 9, and through the agency of this means, the cap may be adjusted to various sized heads. A plate 10 is

45 secured to the rear portion of the crown 5 and is provided with a hook 11 or some other suitable means whereby the cap can be supported when not in use.

Numeral 12 represents the peak of the cap 50 and numeral 13 represents the Z-shaped

frame for supporting a lamp (not shown). The frame 13 may form part of the crown 5 and the lower end thereof is secured to the peak 12 as at 14. The intermediate portion of this frame 13 is provided with a circular-shaped opening 15 from which the slot 16 extends, merging with the elongated opening 17.

A spring 18 is provided for supporting the usual miner's lamp, that is retaining the same 60 against the frame 13. This spring 18 is secured to a vertical member 19 which is fastened to a pair of transversely extending pieces 20, one of which engages with the outer side of the frame, while the other engages 65 the inner side. A pivotal member 21 is also provided on the vertical member 19 and is provided with a finger extension 22 at one end whereby the same can be swung to permit detachment of the spring from the frame 13. 70

Numeral 23 represents a pin container which has its lower end supported within the socket 24. The upper end is engaged within the socket 25, which is provided with a threaded extension 26 disposed through a 75 substantially triangular shaped slot 27 in the frame 13. A winged nut 28 is engageable on this extension 26 and by alining this nut with the large part of the slot 27 the socket 25 can be lifted so that the container 23 can be detached from the frame. This container is adapted to hold pins or needles used for cleaning the burner tips of the lamp.

As is clearly shown in Fig. 2, the top portion of the frame 13 is provided with the 85 elongated slot 29 and the round opening 30. This slot and opening accommodates the socket unit generally referred to by numeral 31. (See Fig. 8.) This socket unit is constructed of a single piece of sheet metal, the same 90 being first formed to provide the barrel 32 which can accommodate the type of lamp employing the usual hook for engaging through the customary opening in the top of the lamp frame. This portion of the socket 95 unit engages into the opening 30 of the frame 13 and from this barrel 32, the sheet is disposed laterally and backwardly to provide the elongated socket 33 for receiving the usual blade type of detent found on some types of 100

lamps. The unit is further formed with the wings 34 which are to be secured to the top side of the frame 13, and with the wings 35—35 and 36—36, which are secured to the intermediate portion of the frame.

Obviously, a miner's cap constructed in accordance with the foregoing invention, will not only have an universal utility, but will also be protective, adjustable, and durable 10 without materially increasing the cost thereof.

While the foregoing specification sets forth the invention in specific terms, it is to be understood that numerous changes in the shape, 15 size and materials may be resorted to without departing from the spirit and scope of the invention as claimed hereinafter.

Having thus described my invention, what I claim as new is:—

20 A lamp supporting means for a miner's cap comprising a frame including an upright portion having a vertically arranged elongated opening therein, a vertically arranged bar located in the lower part of the opening, a 25 transverse bar connected to each face of the vertical bar at the lower end thereof for engaging the inner and outer faces of the upright part of the frame, a clamp connected with the front face of the vertical bar and 30 a bar pivotally connected with the upper end of the vertical bar for engaging the rear face of the upright part of the frame when said pivoted bar is turned into horizontal position to detachably hold the lamp carrying 35 bar in position.

In testimony whereof I affix my signature.

JOHN RUFFING, SR.
